UNITED STATES PATENT OFFICE.

NICOLAJ PETER KREBS, OF BREA, CALIFORNIA.

CASING HEAD.

Application filed April 24, 1923. Serial No. 634,259.

To all whom it may concern:

Be it known that I, NICOLAJ PETER KREBS, a subject of the King of Denmark, and a resident of Brea, county of Orange, State 5 of California, have invented new and useful Improvements in Casing Heads, of which the following is a specification.

This invention has to do with a casing head, and has particular reference to that 10 general type of head adapted to be mounted on a casing, having a drill pipe, or the like, extending into it to pack the drill pipe with the casing.

In drilling wells where there is a drill 15 pipe, or the like, extending downwardly through a casing a head is usually mounted on the casing to carry packing to pack the pipe with the casing. With ordinary heads used for this purpose it is usually incon- 20 venient and difficult to install the packing if the well is flowing, or to renew the packing when it wears or is blown out, and it is impossible to close the casing if the drill pipe is drawn or blown out of the casing.

25 It is an object of this invention to pro- vide a head for use in a situation such as I have above referred to, which has a reliable effective auxiliary packing means that can be be put in operation to relieve or to oper- 30 ate in place of the regular packing.

Another object of this invention is to pro- 35 vide a head of the general character above referred to having means operable to com- pletely close the casing upon removal of the drill pipe.

Another object of the present invention is 40 to provide a simple, novel and effective operating means for the auxiliary packing whereby it can be easily and quickly put into or taken out of operation and whereby it may be controlled from a point removed from the head.

Another object of my present invention is 45 to provide means in a head of the character above specified whereby the auxiliary pack- 50 ing and closing means operate automatically upon the regular packing being blown out.

The objects and features of my invention 55 will be best and more fully understood from the following detail description of a typical preferred form of the invention, throughout which description reference is had to the accompanying drawings, in which:

Fig. 1 is a vertical sectional view showing 55 a head embodying the present invention in

operating position on a casing and drill pipe, the auxiliary packing means being shown in operating position;

Fig. 2 is a view similar to Fig. 1, the auxiliary packing means being shown out 60 of operation;

Fig. 3 is a side elevation of the head illus- 65 trated in Figs. 1 and 2, being a view showing the operating means for the auxiliary packing; and

Fig. 4 is a detail sectional view taken as indicated by line 4-4 on Fig. 1.

Throughout the drawings numeral 10 designates a typical well casing, numeral 11 a drill pipe arranged to extend downwardly 70 in the casing 10, and numeral 12 the head embodying the present invention which is adapted to be mounted on the upper end of the casing 10, and to pack the drill pipe 75 with the casing. When I herein refer to a drill pipe, or the like, I mean, of course, to include any device or object that may be arranged in the casing and in connection with which a device such as I herein refer to may be used.

80 The head 12, provided by this invention, includes, generally, a frame, operating or regular packing means 13, carried by the frame to pack the casing with the drill pipe, packing means 14 adapted to be put into operation to relieve or take the place of the regular packing means 13, operating means 15 for the auxiliary packing 14, means 16 for completely closing the casing 90 when the drill pipe is removed therefrom, and means 16' whereby the auxiliary pack- 95 ing is automatically operated upon blowing out of the regular packing.

The frame of the head 12 includes a body 17, an annular flange part 18 extending downwardly from the bottom 19 of the body 17, and an annular flange part 20 extending upwardly from the top 21 of the body 17 concentrically with the flange part 18. The flange part 18 is screw threaded 100 to receive the casing 10, as I have clearly illustrated in the drawings. The frame is preferably a casting, having its various parts shaped and proportioned to accommodate and properly carry the various other parts 105 of the device, as I will hereinafter describe.

The regular packing 13 includes an annular body of packing material 22 adapt- 110 ed to fit around the drill pipe and to be carried in a suitable seat 23 formed in the

upper part of the flange 20. In the particular form of construction illustrated in the drawings, the body of packing 22 may be formed of a body of rubber, or the like, 5 and carried between two metal rings 24 and 24^a. The seat 23 is formed in the flange part from its upper end so that the structure formed by the body of packing and rings can be readily arranged in it from 10 the upper end of the flange. A retaining ring 26^a is screw threaded to the upper end portion of the flange 20 to retain the rings 24 and 24^a and packing 22 in place in the seat 23, and so that it can be tightened to 15 force the ring 24 downwardly so that it expands the body of packing between the seat and drill pipe. As the packing 22 wears away it can be tightened by tightening the retaining ring 26^a and when it is 20 necessary to replace the packing 22 it is merely necessary to remove the retaining ring 26^a and lift the rings 24 and 24^a with the packing 22 out of the seat 23.

The auxiliary packing means 14 includes 25 a body of packing materially adapted to be arranged around the drill pipe in a suitable seat 25 provided in the lower part of the flange 20. In accordance with my invention, the body of packing is formed in 30 two sections 26 which are semicircular in shape and are designed and proportioned so that they fit together to completely fill the space between the seat 25 and drill pipe when arranged in the seat. The packing sections 26 are mounted on carriers 28 arranged and mounted in the body 17 of the frame. The packing sections 26 may be held on the carrier by semicircular plates 29 which are adapted to fit into the bottom 35 of the seat 25 and are connected with the carriers by screws 30 which extend between the plates and carriers and through the packing sections, in the manner clearly illustrated in Figs. 1 and 2 of the drawings. 40 The carriers 28 are pivotally mounted in the body 17, being carried on shafts 31, so that they are movable between a position where they hold the packing sections clear 45 of the seat 25 and drill pipe, as shown in Fig. 2, and a position where they hold the packing sections in the seat, as illustrated in Fig. 1. When the shafts 31 are related 50 to the seat in the particular manner illustrated in the drawings, the plates 29 are cut away at 29^a so that they will clear the pipe when the carriers are operated. The carriers 28 are preferably more or less 55 loosely mounted on the shafts 31 so that the packing sections are more or less free 60 to center or seat themselves in the seat 25 when they are put into operation. The shafts 31 extend through the body 17 between the side walls 38 and 39 thereof, in 65 the manner clearly illustrated in Fig. 4. One end of each of the shafts 31 is carried

in a suitable bearing boss 40 provided on the wall 38, while the other end projects from the body through a suitable stuffing box 41 carried by the wall 39. In the form of the invention illustrated in the drawings, 70 the carriers, although loosely mounted on the shafts, are operatively connected with the shafts so that they are swung, as between their open and closed positions, which I have above described, by rotation of the 75 shafts. In the drawings I have illustrated the shafts 31 of irregular configuration where they extend through the body, and have shown them extending more or less loosely through openings 50 of similar configuration, provided in the bosses 51 of the carriers. This particular manner of mounting the carriers 28 on the shafts 31 is particularly simple and allows proper seating 80 of the packing sections and yet makes the 85 carriers operable from the shafts.

The operating means which I have provided for the auxiliary packing means, includes an interconnection between the shafts 31 and an operating lever 52. The interconnection between the shafts 31 is such as to cause them to operate in synchronism in opposite directions so that they will cause simultaneous operation of the carriers 28 and, in the particular form of the invention illustrated in the drawings, includes gear segments 53 secured on the ends of the shafts projecting from the body so that they mesh, as illustrated in Fig. 3. The operating lever 52 may be connected with the shafts or segments in any desired manner, for instance, it may be formed integral with one of the gear segments, as I have clearly illustrated in the drawings. In practice the operating lever 52 may be actuated by hand, or it may be operated from a point removed from the device through a suitable rod or other connection.

The means 16 provides for completely closing the head, and, therefore, the casing, 110 in the event that the drill pipe is removed from the casing. This means includes two gates 60 adapted to be positioned so that they close the opening through the auxiliary packing means when said auxiliary packing means is in the operating position. In the particular form of the invention illustrated 115 in the drawings, the gates are pivotally mounted on the carriers 28, as I have clearly illustrated in Figs. 1, 2, and 4 of the drawings. The outer ends 61 of the gates 60 are straight and flat and are adapted to come together when the gates are closed. In accordance with the preferred form of the invention, I provide packing means in connection 120 with the gates so that they tightly close the opening through the auxiliary packing means. This packing means may include two semi-circular bodies of packing material 63 mounted on the faces of the gates so 125 130

that they extend into seats 64 formed in the carriers 28 when the gates are closed. The bodies of packing 63 may be mounted on the gates by suitable bolts 65. The gates are preferably loosely pivotally connected with the carriers by means of suitable shafts 66 so that they are more or less freely movable to allow the packings 63 to properly seat in the seat 64. The shafts 66 are carried by lugs 67 which project from the backs of the carriers 28. I preferably provide springs 69 in connection with the gates 60 to normally yieldingly hold them in the closed position where the packings 63 are in the seats 64. The springs 69 allow the gates to be held out by the drill pipe when the auxiliary packing is arranged in operative position around a drill pipe and causes the gates to close automatically upon removal of the drill pipe. It will be obvious that the invention might be carried out by providing a single gate sufficiently large to completely close the opening through the auxiliary packing means, however, this construction would necessitate making the body of the frame larger than is required by the construction I have described.

I provide a by-pass pipe 70 between the body portion of the frame and the middle portion of the flange 20 so that pressure can be communicated between these parts of the device. I provide a control valve 71 in the by-pass 70 so that the communication of pressure can be controlled.

The means 16^a provided for causing the auxiliary packing 14 to automatically move to operating position in the event that the regular packing blows out, includes baffles 80 arranged in the body so that they will direct fluid flowing through the body of the head from the casing to the rear of the carriers 28 so that they are swung up to the closed or operating position. The baffles 80 may be supported in the body 17 by suitable ribs 81, and may in any given case be designed and proportioned so that they direct the fluid in the desired manner.

In operation on the head 17 is arranged on the upper end of the casing. The regular packing 13 is arranged in the seat 23 and the retaining ring 26 is screw threaded on the flange to retain the packing in place and to expand it so that it packs the drill pipe. When the drill pipe is in operation it is normally preferred that the auxiliary packing means be maintained in the released position, that is, where the carriers 28 are out or down, as I have clearly illustrated in Fig. 2. However, at any time when it is desired to relieve or replace the regular packing 13 the auxiliary packing may be easily and quickly put into operation by operating the shafts 31 in the proper direction through the operating means 15. As soon as the auxiliary pack-

ing is moved into operating position the pressure from the casing will hold it there and will expand the packing sections 26 so that they pack the drill pipe tightly. When the auxiliary packing 14 is in operating position the regular packing 13 can be removed and replaced as desired. When it is desired to release the auxiliary packing, for instance, when the regular packing has been put into operating condition, the control valve 71 in the by-pass 70 is open so that the pressure is equalized at the two sides of the auxiliary packing, allowing the gates to open by gravity or to be swung open by actuation of the operating means 15. If at any time the regular packing 13 blows out when the auxiliary packing 14 is out of operation the baffles 80 will direct the flow of fluid to the back of the carriers 28 so that they are swung up to the operating position, or, if this means fails to work the auxiliary packing can be easily and quickly thrown into operation through the operating means. Further, if at any time the drill pipe is pulled or blown out of the head the auxiliary packing 14 may be put into operating position causing the gates 60 to come into position where they close the opening through the auxiliary packing. It will be obvious, of course, that when the drill pipe is removed there is nothing to prevent the springs 69 from moving the gates to the position where they close the opening in the auxiliary packing.

Having described only a typical preferred form of my invention I do not wish to limit myself to the specific details hereinabove set forth but wish to reserve to myself any changes or variations that may appear to those skilled in the art or fall within the scope of the following claims:

Having described my invention, I claim:

1. A head adapted to be mounted on a casing having a drill pipe in it including a frame adapted to be mounted on the casing, packing means carried by the frame to engage the pipe, a tapered seat in the frame around the pipe, and auxiliary packing carried by the frame to be operable to position in the seat to engage the pipe.

2. A head adapted to be mounted on a casing having a drill pipe in it including a frame adapted to be mounted on the casing, packing means carried by the frame to engage the pipe, a tapered seat in the frame around the pipe, and auxiliary packing carried by the frame embodying sections of packing loosely pivotally mounted so that they are operable between a position where they are separated and clear of the pipe and a position where they are together and in the seat to operatively engage the pipe.

3. A head adapted to be mounted on a casing having a drill pipe in it including a frame, packing means carried by the frame

to operatively engage the pipe, auxiliary packing means carried by the frame so that it is operable to operatively engage the pipe at a point spaced below the first mentioned packing means, and a by-pass between the space between the two packing means and the lower side of the auxiliary packing means.

4. A head adapted to be mounted on a casing having a drill pipe in it including a frame, packing means carried by the frame to operatively engage the pipe, auxiliary packing means carried by the frame so that it is operable to operatively engage the pipe at a point spaced below the first mentioned packing means, a pressure transmitting connection between the space between the two packing means and the under side of the auxiliary packing means, and control means for the connection.

5. A head adapted to be mounted on a casing having a drill pipe in it including a frame including a body adapted to be mounted in the casing and a part extending upwardly from the body, packing carried by said part to operatively engage the pipe, auxiliary packing carried by the body to be operable to a position where it operatively engages the pipe at a point spaced below the first mentioned packing, and a by-pass between the body below the auxiliary packing and said part at a point between the two packings.

6. A head adapted to be mounted on a casing having a drill pipe in it including a frame including a body adapted to be mounted on the casing and a flange part extending upwardly from the body concentric with the casing, packing carried by said flange part so that it operatively engages the pipe and is removable from the upper end of said part, two shafts extending into the body at opposite sides of the pipe, carriers arranged in the body and mounted on the shafts so that they are swung by rotation of the shafts, a downwardly facing seat in the frame, packing segments carried by the carriers and adapted to be carried by them into position in the seat so that they extend around and operatively engage the pipe, and means for deflecting the flow of fluid through the head back of the carriers so that the carriers are actuated to position where the segments are in the seat upon outward flow of fluid through the head.

7. A head adapted to be mounted on a casing having a drill pipe in it including a frame adapted to be mounted on the casing, packing means carried by the frame to engage the pipe, auxiliary packing means carried by the frame and adapted to be actuated to engage the pipe, and baffles whereby the auxiliary packing means is automatically actuated to engage the pipe upon flow of fluid outwardly through the head.

8. A head adapted to be mounted on a casing having a drill pipe in it including a frame adapted to be mounted on the casing, packing means carried by the frame to engage the pipe, auxiliary packing means carried by the frame to be actuated to engage the pipe including packing sections pivotally mounted and adapted to swing from positions where they are out of engagement with the pipes to a position where they operatively engage the pipe, and baffles in the frame to direct fluid flowing through the frame back of the packing segments when they are in the first mentioned position to move them to the position where they operatively engage the pipe.

9. A head adapted to be mounted on a casing having a drill pipe in it including a frame adapted to be mounted on the casing and having an opening through it to pass the pipe, packing means carried by the frame at the opening to operatively engage the pipe, auxiliary packing means carried by the frame so that it is operable to operatively engage the pipe, and means in connection with the auxiliary packing means to close the head upon removal of the pipe.

10. A head adapted to be mounted on a casing having a drill pipe in it including a frame adapted to be mounted on the casing and having an opening through it to pass the pipe, packing means carried by the frame at the opening to operatively engage the pipe, auxiliary packing means mounted in the frame to be actuated to a position where it extends around the pipe to operatively engage it, and means for closing the opening through the auxiliary packing means upon removal of the pipe.

11. A head adapted to be mounted on a casing having a drill pipe in it including a frame adapted to be mounted on the casing and having an opening through it to pass the pipe, packing means carried by the frame at the opening to operatively engage the pipe, packing means mounted in the frame to be actuated to a position where it extends around the pipe to operatively engage it, and means for automatically closing the opening through the auxiliary packing means upon removal of the pipe.

12. A head adapted to be mounted on a casing having a drill pipe in it including a frame adapted to be mounted on the casing so that the pipe extends through it, packing means carried by the frame to engage the pipe, auxiliary means carried by the frame so that it is operable to operatively engage the pipe embodying separable packing sections and carriers for the packing sections pivotally mounted in the frame so that they are movable to carry the sections into position where they cooperatively engage and extend around the pipe, and gates carried by the carriers so that they are movable

into position where they cooperate to close the opening through the packing sections when the pipe is removed.

13. A head adapted to be mounted on a casing having a drill pipe in it including a frame adapted to be mounted on the casing, packing means carried by the frame and adapted to be actuated to engage the pipe, auxiliary packing means operable to engage the pipe and baffles whereby the auxiliary packing means is automatically actuated to engage the pipe upon flow of fluid outwardly through the head.

14. A head adapted to be mounted on a casing having a drill pipe in it including a frame having a tapered seat around the drill pipe, packing, means mounting the packing in the frame so that it is pivotally movable into the seat to engage the drill pipe and is movable longitudinally of the drill pipe in the seat.

15. A head adapted to be mounted on a casing having a drill pipe in it including a frame, packing carried by the frame and having an opening to pass the drill pipe, carriers for the packing movable into and out of position where the packing packs around the drill pipe, and means carried by the said carriers for closing the hole in said packing upon removal of the drill pipe.

16. A head adapted to be mounted on a casing having a drill pipe in it including a

frame, packing carried by the frame and having an opening to pass the drill pipe, said packing being movable into and out of position where it packs around the drill pipe, and gates pivotally carried by said first mentioned packing to close the hole in said first mentioned packing upon removal of the drill pipe.

17. A head adapted to be mounted on a casing having a drill pipe in it including a frame, packing carried by the frame and having an opening to pass the drill pipe, said packing being movable into and out of position where it packs around the drill pipe, means carried by said packing operable to close the hole in the packing and means normally yieldingly tending to operate said means.

18. A head adapted to be mounted on a casing having a drill pipe in it including a frame, packing carried by the frame and having an opening to pass the drill pipe, said packing including two pivotally mounted sections movable to a position where they engage around the pipe, and packing sections pivotally mounted on the first mentioned sections operable to close the said opening when the pipe is removed.

In witness that I claim the foregoing I have hereunto subscribed my name this 11th day of April, 1923.

NICOLAJ PETER KREBS.
